(57) **CLAIM**

The ornamental design for an extension cord reel, as shown and described.

DESCRIPTION

FIG. 1 is a top and side perspective view of an extension cord reel showing my new design, the phantom line showing of an extension cord forming no part of the claimed design;

FIG. 2 is a top plan view thereof;

FIG. 3 is a bottom plan view thereof;

FIG. 4 is an elevational view thereof from the lower left of FIG. 1; and,

FIG. 5 is a side elevational view thereof from the right of FIG. 4, the side opposite that shown in FIG. 5 being the mirror image thereof.
